UNITED STATES PATENT OFFICE.

CARL JOHNSON BJERKNES, OF ARKDALE, WISCONSIN.

REPEATING FIRE-ARM.

SPECIFICATION forming part of Letters Patent No. 357,170, dated February 8, 1887.

Application filed May 17, 1886. Serial No. 202,453. (No model.)

To all whom it may concern:

Be it known that I, CARL JOHNSON BJERKNES, of Arkdale, in the county of Adams and State of Wisconsin, have invented a new and Improved Repeating Fire-Arm, of which the following is a full, clear, and exact description.

The object of my invention is to provide a new and improved repeating fire-arm, which is loaded automatically and throws the firing-pin back to its place by the back action of the charge, and also discharges the cartridge-shell automatically.

The invention consists of a cylinder sliding in the breech-block, of a firing-pin sliding in the cylinder and in a bushing on the breech-block, and of a device for automatically loading and discharging the cartridge-shell.

The invention also consists of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a longitudinal central section of my improvement. Fig. 2 is a sectional plan view of the same on the line $x-x$, Fig. 1. Fig. 3 is a side elevation of the same. Fig. 4 is a vertical transverse section of the breech-block through the recesses $E'-E''$, showing the manner of ejecting the cartridge.

The barrel A is provided with the bore B, which terminates at its rear end in the annular recess B', into which fits the straight cartridge V, so as to prevent the latter from entering the bore B when hit by the firing-pin C, which is provided on its front end with a collar, C', sliding in a cylinder, D, fitted to slide in a recess, E', of the breech-block E, screwed upon the rear end of the barrel A and fastened with the same into the stock F. The rear end of the firing-pin C is guided in the bushing H, screwed into the breech-block E, and is provided with a shoulder, C', which engages with the upper end of the lever I, operated by the trigger J and a spring, K, in the usual manner.

A spring, L, is placed between the stationary bushing H and the head D' of the cylinder D, and another spring, M, is coiled on the firing-

pin C, resting with one end against the inner end of the bushing H and with its other end against the collar C' of the firing-pin C. The closed end D' of the cylinder D rests against the cartridge V, and is provided with a central aperture, through which passes the pointed end of the firing pin when striking the cartridge.

The stock F has an inclined tube, N, in which slide the cartridges V, one above the other, being pressed upward by a spring, O, acting against a cap, P, having a knob, Q, which projects through a recess, N', in the side of the tube N. The upper end of the inclined tube N terminates in a recess, E', formed on the under side of the breech block E, in which recess E' the cartridge is held before being placed in the annular recess B' of the barrel A by the action of the springs R, which press the cartridge upward against the under side of the cylinder D.

In the side of the breech-block E is formed a recess, E', which communicates with the recess E', and is covered by a slide, S, provided with a knob, T, having an angular arm, T', which engages with a spring, U, having a bent part, U', by which the slide S can be held in an open position, the bend U' of the spring U engaging the recess U' formed in the side of the breech-block E.

The operation is as follows: As shown in Fig. 1, the fire-arm is in the position to be fired, which is done by pressing on the trigger J, which acts on the lever I, which releases the firing-pin C. The latter is thrown forward by the action of the spring M, its front end sliding in the cylinder D, and the point of the firing-pin passing through the central aperture in the end D' of the cylinder D and exploding the cartridge, which is held in place by the cylinder D and prevented from moving into the bore B by being fitted into the annular recess B'. When the cartridge explodes, the empty shell will be forced rearward, and with it the cylinder D, and as soon as the shell is in register with the side opening, E', the springs R R will force the cartridge 1 (see Fig. 4) upward, and said cartridge will force the empty shell 2 out through the opening E'. As soon as the cartridge 1 is in alignment with the cylinder D said cartridge will be forced

forward into its chamber B' and a new cartridge will be passed from the magazine into the recess E', when the gun will again be in condition for firing. In its forward or return movement the flange D' of the cylinder D will engage the angle-arm T' and force the slide over the opening E'.

Having thus fully described my invention, I claim as new and desire to secure by Letters Patent—

1. In a repeating fire-arm, the combination of a barrel and a breech-block with a cylinder sliding in the breech-block, and a spring placed between the cylinder and a bushing of the breech-block, substantially as shown and described.

2. In a repeating fire-arm, the combination of a breech-block and a cylinder sliding in the said breech-block with a firing-pin sliding in a bushing of the breech-block and the cylinder, and a spring placed between the bushing and a collar on the firing-pin, substantially as shown and described.

3. In a repeating fire-arm, the combination of a barrel and a breech-block with a cylinder, sliding in the said breech-block, a firing-pin sliding in a bushing of the breech-block and in the said cylinder, and springs operating the said cylinder and the firing-pin, respectively, substantially as shown and described.

4. In a repeating fire-arm, the barrel A, having the bore B and the annular recess B', and the breech-block E, provided with the bushing H, in combination with the cylinder D, sliding in the breech-block, the firing-pin C, having a collar and a shoulder which engages with a lever operated by the trigger, and the springs L and M, operating on the cylinder D and the firing-pin C, substantially as shown and described.

5. In a repeating fire-arm, the cylinder D, sliding in the breech-block, and the firing-pin

C, having the shoulder C', in combination with the lever I, the spring K, forcing the inner end of the lever downward, and the trigger J, having its inner end engaging the lower face of the said inner end of the lever, substantially as shown and described.

6. The breech-block E, having a recess, E', and a side opening, E', leading therefrom, and the cylinder D, sliding in said recess and having the head D' on its inner end, and the slide S, adapted to close the opening E', and provided with a knob, T, on its outer face, having an angle-arm, T', in the forward path of the head D', substantially as set forth.

7. The breech-block E, having the recess E', an opening, E', leading sidewise therefrom, and a notch, U', near the rear end of said side opening, and the cylinder D, sliding in the recess E', and having a head, D', and the slide S, adapted to close the opening E', and provided with the spring U, for engaging the notch U', and with the knob T, having an angle-arm, T', in the forward path of the head D', substantially as set forth.

8. In a repeating fire-arm, the breech-block E and the cylinder D, sliding in the breech-block E and operated by the spring L, in combination with the springs R, supporting the cartridges from below at their front and rear ends, substantially as shown and described.

9. In a repeating fire-arm, the stock F, provided with the inclined tube N, in combination with the spring O, the cap P, and the springs R R, placed one in advance of the other in the bottom of a cartridge-receiving recess at the juncture of said tube with the breech-block, substantially as shown and described.
